United States Patent Office

Des. 192,738
Patented May 8, 1962

192,738

TABLE

David Patience, Jr., Chicago, Ill., assignor to Rembrandt Lamp Corporation, Chicago, Ill., a corporation of Illinois

Filed Jan. 30, 1961, Ser. No. 63,751

Term of patent 7 years

(Cl. D33—14)

Fig. 1.

Fig. 2.

Fig. 3.

FIG. 1 is a perspective view of a table showing my new design; and

FIG. 2 is a cross-sectional view taken on lines 2—2 of FIG. 1.

FIG. 3 is a partial sectional view along the line 3—3 of FIG. 1.

I claim:

The ornamental design for a table, substantially as shown.
